UNITED STATES PATENT OFFICE.

JOHN V. ABRONSKI, OF PHILADELPHIA, PENNSYLVANIA.

MOTHER AND CHILD IDENTIFICATION MEANS.

Application filed February 25, 1921. Serial No. 447,762.

To all whom it may concern:

Be it known that I, JOHN V. ABRONSKI, a citizen of the United States, residing at Philadelphia, in the county of Philadelphia and State of Pennsylvania, have invented 5 new and useful Improvements in Mother and Child Identification Means, of which the following is a specification.

The object of my present invention is the 10 provision of means calculated to absolutely identify an infant with its mother from the time of birth with a view to precluding confusion among infants born in hospitals where the infants are ordinarily kept in one 15 room and away from their respective mothers except at feeding times.

To the attainment of the foregoing, the invention consists in the improvement as 20 hereinafter described and definitely claimed.

In the accompanying drawings, forming 25 part hereof:—

Figure 1 comprehends a couple of identification devices made in accordance with my invention.

Figure 2 is a view taken longitudinally 30 through one of the seals comprised in the devices.

Figure 3 is a perspective showing one sealing tube as it appears precedent to being 35 crimped.

Similar numerals of reference designate 40 corresponding parts in all of the views of the drawings.

In the best practical embodiment of my 45 invention of which I am cognizant two of the devices are employed for a mother and her child. The said devices are identical in characteristics with the exception that when deemed expedient the cable of the infant device may be made shorter than the cable of the mother device. This, however, is not of the essence of my invention inasmuch as the cables may originally be of the same length without affecting the invention 50 as claimed. In addition to a cable 1 which may be made of chain or other appropriate material, each device comprises a disk 2 and two sleeves numbered 3 and 4, respectively.

In accordance with the scheme of my 55 invention, immediately after a mother gives birth to a child one of the devices shown in Figure 1 is applied to the neck, leg or arm of the mother, and the other device is applied to the neck, leg or arm of the infant. 55 In each case after the cable 1 is passed for instance around the neck of the mother or

infant, as the case may be, the tubular or sleeve like seal 4 is appropriately positioned on the lapped end portions of the cable, after which the seal 4 is subjected to 60 the pressure of an appropriate instrument and is crimped as indicated by 5, if deemed necessary, so as to preclude disconnection of the cable from the neck of the mother or infant without making it apparent that the 65 connection of the device to the mother or the infant has been tampered with.

The seal 3 of each device may be and 70 preferably is applied and subjected to pressure in the same manner as the seal 4. In each device it will be appreciated that the seal 3 serves to retain the disk 2 in the bight of a loop formed of the cable 1, the cable 1 being passed through an aperture 6 in the disk, and movement of the disk on the cable 75 being limited by the seal 3. This confinement of the disk 2 in a very short bight portion of the cable 1 contributes to averting the possibility of the disk 2 being surreptitiously removed from the cable and replaced 80 by another disk without the substitution being made readily apparent by disfigurement or mutilation of the bight portion of the cable. The practical advantage of this will 85 be better appreciated when it is stated that the tags of a couple or pair of the devices bear identical numbers or other identical symbols so that the identity of the infant with the mother and vice versa, may be established at the time of birth and thereafter 90 maintained without liability of such identification being destroyed.

It will be apparent from the foregoing 95 that when a couple of my novel identification devices are put into use in the manner described there is absolutely no liability of a strange infant being foisted on a mother as her own infant. This is due to the fact that when a couple of my novel devices are secured on a mother and her child in the manner described there is no liability of the devices being casually separated from the mother and child and no liability of either disk 2 being purposely detached from the cable 1 without the removal of the disk 100 and the substitution of another disk being manifest.

In case of twins, two sets of symbols will 105 be used, the mother being tagged with two different symbols, and each twin being tagged with a similar symbol as that worn 110 by the mother.

While I prefer to employ the construction herein illustrated and described I would have it distinctly understood that it is within the purview of my invention to construct the devices in any manner calculated to preclude removal of the cable from a mother or child, or the removal of either disk from its cable and the substitution of another disk without mutilation of the devices to such an extent as to make the substitution apparent.

Having described my invention, what I claim and desire to secure by Letters-Patent, is:—

1. Means for identifying a mother with her infant and vice versa from the birth of the infant, comprising two devices, each device being made up of a disk having near its edge an aperture, a chain passed through the aperture of the disk, a seal sleeve receiving the stretches of the chain and arranged adjacent to the edge of the disk and

crimped at intervals in its length, and a second seal sleeve receiving the end portions of the chain and crimped at intervals in its length.

2. Means for identifying a mother with her infant and vice versa from the birth of the infant, comprising two devices, each device being made up of a disk bearing a symbol and having adjacent to its edge an aperture, a cable passed through said aperture and receiving an edge portion of the disk in a bight portion of the cable, means permanently fastening together the end portions of the cable, and a sleeve seal receiving the stretches of the cable and arranged immediately adjacent to the edge of the disk and permanently fastened of itself to the cable whereby movement of said sleeve relative to the disk is precluded.

In testimony whereof I affix my signature.

JOHN V. ABRONSKI.
